VEHICLE BRAKE DRUM

Leonard Troy, 5 Pen-Y-Bryn Drive, Scranton, Pa.

Filed July 9, 1962, Ser. No. 70,837

Term of patent 14 years

(Cl. D14—30)

FIG. 1

FIG. 2

FIGURE 1 is a rear elevational view of a vehicle brake drum showing my new design;

FIGURE 2 is a front elevational view thereof;

FIGURE 3 is a section taken on line 3-3 of FIGURE 1;

FIGURE 4 is a fragmentary top plan view of a portion of the new brake drum;

FIGURES 5-8 are enlarged fragmentary sectional views showing modified forms of the circumferentially disposed rib as shown in FIGURE 3; and

FIGURE 9 is a section taken on line 9-9 of FIGURE 8.

The characteristic features of my design reside in the outer annular band in combination with the axially disposed upstanding fins, said annular band encompassing and intersecting the fins and being connected to the outer wall of the brake drum by a thin web, as shown.

I claim:

The ornamental design for a vehicle brake drum, as shown and described.
